UNITED STATES PATENT OFFICE.

EDWARD WESNER, OF PRINCEVILLE, ILLINOIS.

COMBINED WASHING AND WRINGING MACHINE.

SPECIFICATION forming part of Letters Patent No. 230,683, dated August 3, 1880.
Application filed May 13, 1880. (No model.)

To all whom it may concern:

Be it known that I, EDWARD WESNER, of the town of Princeville, in the county of Peoria, in the State of Illinois, have invented a 5 Combined Washing - Machine and Clothes-Wringer; and I do hereby declare that the following is a full, clear, and exact description thereof, reference being had to the annexed drawings, making a part of this specification, 10 in which like letters of reference refer to like parts, and in which—

Figure 1 represents a longitudinal elevation; Fig. 2, a plan view; Fig. 3, a vertical cross-section on dotted line *a a*, Fig. 2; Fig. 15 4, a view of substitute roller *O* for the roller *E*.

This invention belongs to that class which combines a washing-machine and a clothes-wringer in one machine; and it consists in the combination of two parallel pairs of rollers, 20 the upper roller of one of said pairs having a longitudinal motion along its bearings and upon its fellow below it for rubbing purposes. Said upper rollers obtain rotary motion by pressure upon their fellow rollers beneath, 25 and are geared for pressure thereon in the ordinary mode by means of braces and screws, &c. The lower rollers are the motors, and are engaged with each other by means of an idle pinion meshing into the teeth of terminal pinions at the end of the respective lower rollers, 30 the axle of one of which bears a wrench, while the same axle at its other end finishes in a bevel-pinion engaged with a similar pinion having a crank-pin which moves a rod which reciprocates lengthwise the roller above mentioned. One pair of said rollers (used for 35 wringing) are made with longitudinal flutes or ribs, and the lowermost roller of the opposite pair is fluted or ribbed circularly, as well 40 as is the substitute roller used above it, used in place of the smooth roller, as desired. The machine is submerged in suds and fixed to the bottom of the tub or washing-box, the clothes being passed back and forth between each 45 pair of rollers by means of a reciprocation of the crank, one of the rollers, combining its longitudinal motion with its rotary motion, assisting the rubbing process in a kind of spiral motion.

50 In the drawings, which represent one of the forms in which I construct this machine, *A* is

the frame or base, made of any convenient form, fitted to support the two pairs of horizontal rollers *D E* and *F G*. Attached to said frame are the long horizontal clothes-guards *a b d*, of the usual form, to prevent the clothes from passing beneath the bottom rollers, and the fingers *e f g*, to prevent the same from getting entangled beyond the ends of the respective rollers, and a support, *h*, to 60 hold the pinion *N*.

B C are two pairs of slotted standards, with the usual cross-braces *i i* and pressure-bar *k*, moving in the slots of said respective standards, each bar fitted with the usual socketed rods *l*, ending in the bearings *n*, which are extended or pressed downward upon the respective roller-axes by means of springs *m*, coiled upon said bearings *n*, in conjunction with the hand-screws *o o*.

D is a horizontal circumferentially corrugated or channeled roller, of wood, or wood covered with rubber, journaled at either end in or near the base of the respective standards *B B*; *E*, a roller, of wood or other material, covered with rubber, if desired, resting upon said roller *D*, so as to revolve with it, and journaled in its respective blocks or bearings *n n*, mentioned above, and capable of longitudinal motion in the latter by means of the frame *K* and a rod, *L*, connecting it with the pin of the bevel-pinion *N*, which is geared to the bevel-pinion *M* on the end of the axle of the ribbed roller *F*. Said roller *F* is fluted lengthwise, and, like roller *D*, is journaled at 85 either end in or near the base of the respective standards *C* by means of its axle *H*, bearing a crank, *p*, and pinion *I'*.

G is the fellow roller to *F*, similarly fluted, and rides upon it, (roller *F*), by means of its 90 axle, in the respective bearings *n* of the respective pressure-rods *l l* of the bar *k* of the standards *C*.

H is the crank-axle of roller *F*, *p* the crank, and *I'* a pinion upon said axle engaging 95 with the idle pinion *I²*, which in turn engages with pinion *I³* on the axle of roller *D*. The two rollers *F G*, after washing and being elevated above water, are finally used to wring out the water from the clothes.

The operation of this machine is as follows: The rollers are submerged in the tub or box

containing suds, &c., and may be fastened to the bottom of the same. The clothes are introduced between both pairs of rollers at once, and are carried back and forth in the same 5 manner by means of a forward-and-backward turn of the crank or winch *p* alternately, during which the roller *E* passes back and forth over the clothes by means of the frame *K*, rod *L*, and pinion *N*, geared to the pinion *M* on 10 the winch-axle *H*, so giving by the two motions an extra rubbing power to said roller *E*, which function may be increased by substituting for the latter roller the substitute roller *O*, Fig. 4.

15 What I claim as my invention is—

1. In a washing-machine, the combination of the lower roller, *D*, with roller *E*, connected by frame *K* and rod *L*, and with pinions *N* *M*, with motive-roller *F*, or its axle *H*, con-

nected by chain of pinions *I' I² I³* to said roller *D*, substantially as and for the purposes described.

2. In a washing-machine, the combination and arrangement of the roller *D*, pinions *I³ I² I'*, roller *F*, bevel-pinions *M N*, rod *L*, reciprocating frame *K*, and roller *E*, said roller *E* mounted in a well-known mode in the standards *B B*, as likewise the upper roller, *G*, in the standards *C C*, as and for the purposes described. 30

In testimony that I claim the foregoing I have hereunto set my hand this 15th day of April, A. D. 1880.

EDWARD WESNER.
